DESIGN.

F. MANKEY.

PANEL.

No. 17,184.

Patented Mar. 15, 1887.

UNITED STATES PATENT OFFICE.

FREDERICK MANKEY, OF WILLIAMSPORT, PENNSYLVANIA.

DESIGN FOR A PANEL.

SPECIFICATION forming part of Design No. 17,184, dated March 15, 1887.

Application filed December 30, 1886. Serial No. 223,057. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photograph, forming part hereof.

My design consists in the square elevations A, appearing in rows diagonally upon the panel. The edges B of said elevations are stepped, so that each elevation has the appearance of a series of more than two superposed elevations of gradually smaller area. Four steps on the side or edge of each elevation are represented. The upper surface of said elevations is flat.

I prefer to show the general outline of the raised design formed by the diagonal rows of elevations in the shape of a rectangle, as represented in the photograph, and to this end

there appear at the extremities of the rows of elevations triangular elevations C and D, also showing stepped edges or sides to correspond with the stepped sides of elevations A. Some 25 of these triangular elevations, as C, are in the form of isosceles triangles. Others, located at the corners of the panel, are in the form of right-angled triangles. Between the rows of elevations appear channels E.

I claim—

The design for a panel, substantially as herein shown and described, which consists in the rectangular elevations A, having sides or edges B, showing more than two regular steps and appearing in rows diagonally the panel, with intermediate channels, E.

FREDERICK MANKEY.

Witnesses:

C. F. MANKEY,
LEONHARD KNAUSS.
